UNITED STATES PATENT OFFICE.

WILLIAM H. NICHOLSON AND WALTER S. ANDRE, OF TAFT, CALIFORNIA.

BAILER SOCKET.

Application filed February 18, 1924. Serial No. 693,571.

To all whom it may concern:

Be it known that we, WILLIAM H. NICHOLSON and WALTER S. ANDRE, citizens of the United States, residing at Taft, county 5 of Kern, State of California, have invented certain new and useful Improvements in Bailer Sockets; and we do declare the following to be a full, clear, and exact description of the same, reference being had to the 10 accompanying drawings, and to the characters of reference marked thereon, which form a part of this application.

This invention relates to improvements in tools used in connection with well drilling, and particularly to that class of device 15 known as fishing tools.

The principal object of our invention is to produce a tool of this general character especially intended to grip the bails of 20 bailers which may have been lost down the well, though it is also well adapted to engage and grip any other relatively small and flat objects, such as pieces of disc-drills and the like.

Other objects of our invention are to 25 mount the gripping jaws of our tool so that a very firm grasp on the article being fished for will be automatically had, and to form the jaws so that the piece being engaged will be gripped over a considerable portion 30 of its area with equal intensity and pressure throughout.

A further object of the invention is to 35 produce a simple and inexpensive device and yet one which will be exceedingly effective for the purpose for which it is designed.

These objects we accomplish by means of 40 such structure and relative arrangement of parts as will fully appear by a perusal of the following specification and claims.

In the drawings similar characters of reference indicate corresponding parts in the several views:

45 Fig. 1 is a vertical section of the tool.

Fig. 2 is a similar section but taken in the plane of the line 2—2 of Fig. 1.

Fig. 3 is a cross section on line 3—3 of Fig. 1.

50 Referring now more particularly to the characters of reference on the drawings, the numeral 1 denotes a stem or shank threaded at its upper end as at 2 for connection to a standard rod or tool coupling and having 55 an enlarged threaded portion 3 at its lower

end adapted to removably screw into the upper end of a sleeve or socket member 4, whose diameter is close to that of the bore of the well.

Mounted in opposed alinement in the 60 sleeve 4 toward the lower end thereof is a pair of blocks 5, whose adjacent faces are flat and lie in transversely parallel planes, but are formed with an inward slope or taper from both ends toward their center 65 of height, as shown at 6, the slope being symmetrical. The bore of the shell 4, from the lower ends of said blocks to its lower extremity, tapers outwardly as at 7 with a slope substantially the same as that of 70 the block faces to form a flaring mouth.

To securely mount the blocks in the shell and prevent movement thereof in any direction, the faces of the blocks adjacent the shell are vertically ribbed as at 8 for the 75 greater portion of their height, the ribs being seated in countersunk recesses provided in the shell. Intermediate the ends of the ribs are lugs 9 projecting outwardly therefrom and extending to the outside of the 80 shell and fitted into suitable sockets in the latter. Pins 10 or the like are driven through the shell and lugs transversely of the latter, thereby preventing inward movement of the blocks. At the same time, upon 85 the removal of the pins, said blocks may be easily removed or replaced as will be evident.

Slidably mounted for vertical movement along the upper portion of the adjacent 90 sloping faces of the blocks 5 are opposed jaw-blocks 11, the form of mounting employed being preferably the ordinary dovetail arrangement as shown at 12.

The adjacent faces of the jaw blocks are 95 provided with transversely and horizontally disposed teeth 13, extending the full width of the jaws, the adjacent edges of the opposed teeth being parallel both vertically and transversely. From the lowermost 100 teeth to the lower extremity of the jaw blocks the adjacent faces of the latter are cut on a slope substantially parallel to the slope of the lower portion of the corresponding faces of the blocks 5, as shown at 105 14, and are arranged to lie as a continuation of said faces when the jaws are at their lowermost limits of travel, as shown in Fig. 1.

The jaw-blocks are normally held at such 110

lowermost limits by means of a compression spring 15 mounted in the sleeve 4 above said blocks.

This spring bears at its upper end against 5 the shank 1 and its lower end rests on a washer 16 seated on the top of a rigid sleeve 17, the lower end of which rests on both blocks 11.

The shank is bored throughout as shown 10 at 18 for the passage of water therethrough, while as will be evident, an unobstructed path for the water is had throughout the remainder of the tool.

The well-bore below the tool may therefore 15 be readily flushed out, to clear a piece being fished for of any mud or sand which may surround the same.

In operation, the tool is lowered down 20 the well until the bail or other part being fished for passes into the lower end of the shell and is centralized relative to the jaws by the converging faces 6 of the blocks 5.

A sharp downward thrust is then given to 25 the tool, causing the bail to bear against the jaws, the latter then automatically spreading apart against the resistance of the spring 15 and allowing the bail to pass up between the jaw-teeth. Since the opposed upper faces of the blocks 5 on which the jaws slide are symmetrically disposed, the jaws will 30 move so as to maintain their parallel alignment relative to each other and to a vertical plane.

A bail or other flat piece being forced up 35 between the jaws will therefore be engaged on its opposite sides with equal pressure throughout that area of the piece which lies between the jaws, insuring a rigid grip on the piece.

When the tool is raised, the jaws will tend 40 to automatically move down and toward each other in unison and to the same extent, owing to the rigid sleeve 17 resting thereon and which has the pressure of the spring 15 bearing down thereagainst. This insures an even and firm grip being had on the piece being raised.

From the foregoing description it will be 45 readily seen that we have produced such a device as substantially fulfills the objects of the invention as set forth herein:

While this specification sets forth in detail 50 the present and preferred construction of

the device, still in practice such deviations from such detail may be resorted to as do not form a departure from the spirit of the invention, as defined by the appended claims.

Having thus described our invention what we claim as new and useful and desire to secure by Letters Patent is:

1. A fishing tool including a sleeve, opposed jaw members mounted inside the same, yieldable means normally holding said jaws adjacent each other and a common supporting and guide means for said jaws in the sleeve arranged to allow of an upward and diverging movement of the jaws being had while maintaining the adjacent faces of the latter in positive parallel alinement. 65

2. A fishing tool including a sleeve, opposed jaw members mounted inside the same, guide means for the jaw members, independent of the sleeve and mounted therein, and means between said sleeve and guides for holding the latter in definitely fixed relation to the sleeve. 70

3. A fishing tool including a sleeve, opposed jaw members mounted inside the same, guide means for the jaw members, independent of the sleeve and seated therein, and means removably securing said guides to the sleeve. 80

4. A fishing tool including a sleeve, opposed jaw members mounted inside the same, guide means for the jaw members, interposed between the back faces of the jaw members and the sleeve; said guide means having an upward diverging slope and the engaging surfaces of the guides with the jaws being of the same cross sectional size throughout their length, whereby the jaws will be maintained against lateral movement at any position on the guides. 85

5. A fishing tool including a sleeve, opposed jaw members mounted inside the same, guide blocks for the jaws removably seated in the sleeve in opposed alinement to each other, lugs formed with said blocks and extending into sockets provided in the sleeve, and removable transverse pins through said lugs and the sleeve walls to the sides of said lugs. 95

In testimony whereof we affix our signatures:

WILLIAM H. NICHOLSON
WALTER S. ANDRE.
